ATTORNEYS

UNITED STATES PATENT OFFICE.

MICHAEL BERARDINI, OF NEW YORK, N. Y.

CODE MESSAGE.

No. 889,095.

Specification of Letters Patent.

Patented May 26, 1908.

Application filed February 21, 1908. Serial No. 417,002.

To all whom it may concern:

Be it known that I, MICHAEL BERARDINI, a citizen of the United States, and a resident of Fort Wadsworth, Staten Island, borough and county of Richmond, city and State of New York, have invented certain new and useful Improvements in Code Messages, of which the following is a specification.

My invention relates to code messages, and particularly to such as represent financial transactions, the code part of the message being expressed by figures, or being at least capable of translation into figures.

The object of my invention is to provide a safety test in connection with such messages.

The present invention has been designed especially for use in conjunction with code messages such as form the subject-matter of my application for Letters Patent filed in the 20 United States Patent Office December 26, 1907, Serial No. 408,120. In said application I have described how the recipient of the message may ascertain whether or not there is an error in transmission; however, with the 25 means there explained, he could in the case of an error occurring, only discover the fact that there was an error, but he could not locate and correct the error, and would therefore be put to the trouble and expense of 30 asking to have the message repeated.

The object of my present invention is to enable the recipient of the message, by his own tests, not only to ascertain if the message has been correctly transmitted, but to 35 locate and correct an error without consulting the sender of the message.

Reference is to be had to the accompanying drawing in which

Figure 1 illustrates a complete message as 40 written down correctly by the sender; Fig. 2 shows how the test numbers or totals embodied in said message are obtained; Fig. 3 represents the same message as delivered (with errors) to the addressee; Fig. 4 shows 45 how the recipient is enabled, by means of the test totals, to locate and correct the errors which occurred in transmission; and Fig. 5 illustrates an other form of message according to my invention.

The message shown in Fig. 1, in its code part (the three lines after the address) consists of a number of code units X (four in this particular case) each comprising two portions, to wit: a record mark (such as indicated by the reference letter Y) and a value 55 mark (such as indicated by the reference let-

ter Z). In Fig. 1, each unit consists of the same number of elements or figures (five), so that the number of elements (the twenty figures in the line of Fig. 1 after the address) 60 is a multiple of the number of elements contained in each unit. After these code units follows an indication of the number of orders (ordini) represented by the respective code units (4), an indication (lettered T) of the 65 total of amounts or value marks (lire 1700) and an indication (lettered R) of the total of the record marks (1344) together with some symbol (lettered S), such as the word "speciali," which indicates the proper meaning of 70 the value marks. For instance, the use of the word "speciali" as shown in Figs. 1 and 3, may be agreed upon to mean that the first figure of each code unit (naughts excepted) indicates the amount of the order in hundreds of lire, and that the figures to the right of this value mark constitute the record mark or record number. The first code unit 00025 would therefore mean 200 lire and a record 75 number 5. Each of the parties using such 80 messages would have a record book in which the meaning of each record mark or record number would be entered, that is, the names and other particulars, if desired, of the remitter and payee of each order. The record 85 number 5 may mean for instance that the remittance is sent by Gaetano Lucibese to Giuseppe Bonelli of 156 Strada d' Italia, Messina. Sofar as above described, the invention 90 has been disclosed in my prior application above referred to. Now if there was an error in transmission so that the total of first number or value marks ($2+5+7+3$) would not indicate 1700 lire, or that the total of record numbers ($5+46+107+1186$) would 95 not be 1344, the recipient would know that there was an error somewhere, but he would be unable to locate it. To enable him to do this, I have added the test totals (designated by reference letter U) which in the particular example shown in Fig. 1, are

71515193871424.

The manner of obtaining these numbers is shown in Fig. 2. Each of the code units 105 is written in a vertical column (from top to bottom) and the columns are placed side by side so that horizontal rows are formed. Then the figures are added up both vertically and horizontally, to yield the nine totals 110 shown. The number 56 (which is not shown embodied in the message) is only a test as

to the correctness of the addition, as the sum of the four column totals must be equal to the sum of the five row totals.

Now let us suppose that the message Fig. 5 1 is received by the addressee in the form shown in Fig. 3, that is, with two errors in transmission. The addressee knows at once that there are at least two errors, because neither the total of supposed value marks 10 ($1+5+7+3=16$) nor the total of the supposed record marks ($25+46+197+1186=1454$) tallies with the indications Lire 1700 and Speciali 1344. In order to locate the mistake, he arranges the four code units in 15 columns and rows as shown in Fig. 4, and adds up both vertically and horizontally. The total of the first column is found to be 8, instead of 7 as indicated by the test total of the message; similarly the total of the 20 third row is found to be 8 instead of 7. The addressee therefore concludes that the figure in the first column and third row is erroneous, and should be corrected to 0. In the same 25 manner he discovers that the total of the third column, as well as that of the fourth row, are too large by 9, hence he corrects the number at the insertion of the third column and fourth row by subtracting 9 therefrom, making it read 0.

30 It will be obvious that the principle of my invention may be employed in an analogous manner if instead of designating the numerals by the customary figures, I employ a notation in which numbers are expressed by letters. For instance, the numbers 1, 2, 3, 4, 5, 35 6, 7, 8, 9, 0, might be represented by the letters a, b, c, d, e, f, g, h, i z, so that the message Fig. 1 would become (see Fig. 5)

40 zzabezzedfzgaigcaahf
ordini d lire agzz speciali acdd gaeaai chgadbd. This would obviously be corrected in the same manner as described above, in the case of any error in transmission.

45 The advantage of using my new test totals will be evident, in that the addressee is enabled to discover and correct errors without consulting the sender, and thus avoid the trouble, delay and expense which a repetition 50 of the message would entail.

I claim as my invention:

1. A code message comprising a number of code units each consisting of a number of elements having a numerical significance, 55 and test totals indicating the proper results

of the addition of said elements upon the arrangement of said units in columns and rows.

2. A code message, comprising a number of code units each consisting of a number of elements having a numerical significance and test totals indicating the proper sums of the elements of each unit. 60

3. A code message, comprising a number of code units each consisting of a number of elements having a numerical significance, 65 and test totals indicating the proper results of the addition of said elements in rows upon the arrangement of said units in adjacent columns.

4. A code message, comprising a number of code units each consisting of the same number of elements having a numerical significance, each unit being composed of two portions one of which indicates value and the other a record number, the message further comprising an indication of the total value 75 and of the sum of the record numbers, and test totals indicating the proper results of the addition of said elements upon the arrangement of the units in columns and rows. 80

5. A code message, comprising a number of code units each consisting of the same number of elements having a numerical significance, each unit being composed of two portions one of which indicates value and the other a record number, the message further comprising an indication of the total value 85 and of the sum of the record numbers, and test totals indicating the proper sums of the elements of each individual code unit. 90

6. A code message, comprising a number of code units each consisting of the same number of elements having a numerical significance, each unit being composed of two portions one of which indicates value and the other a record number, the message further comprising an indication of the total value 95 and of the sum of the record numbers, and test totals indicating the proper results of the addition of said elements in rows upon the arrangement of said units in adjacent columns. 100

In testimony whereof I have hereunto set my hand in the presence of two subscribing witnesses.

MICHAEL BERARDINI.
